UNITED STATES PATENT OFFICE.

ARTHUR M. RUSSELL, OF MONTREAL, QUEBEC, CANADA.

CAN-OPENER.

No. 911,449.

Specification of Letters Patent.

Patented Feb. 2, 1909.

Application filed March 8, 1907. Serial No. 361,331.

To all whom it may concern:

Be it known that I, ARTHUR M. RUSSELL, of the city of Montreal, in the Province of Quebec and Dominion of Canada, have invented certain new and useful Improvements in Can-Openers, of which the following is a full, clear, and exact description.

This invention relates to can openers, and the object is to provide an inexpensive and efficient tool that will be adapted to open any size or type of can whatever.

The device consists, essentially, of a shank member secured at one end to a suitable handle and having its opposite end provided with a pair of oppositely disposed integral prongs. A cutter member, provided with a plurality of knives of various forms, is slidably mounted on the shank and engages a rack formed on one edge thereof by means 20 of a suitable spring catch or pawl.

In the drawings which illustrate my invention:—Figure 1 is a perspective view of the device. Fig. 2 is a plan view of the cutter member and a portion of the shank. Fig. 3 is a perspective view showing the device as used to open rectangular cans or tins. Fig. 4 is a perspective view showing the method of cutting out the top of a cylindrical can. Fig. 5 is a perspective view 30 showing the method of cutting off the top of a cylindrical can below the edge. Fig. 6 is a longitudinal sectional view of the device showing the spring and pawl.

Referring to the parts, 1 designates the shank member fixed at one extremity to the handle 2 and having its opposite end provided with a pair of oppositely disposed prongs or spurs 3. One edge of the shank is provided with a plurality of teeth 4. The 40 cutter member comprises a sleeve 5 surrounding the shank and adapted to slide back and forth thereon. The cutter member is provided with a plurality of knives preferably formed integral therewith and each adapted to be used in a different manner. The knife 6, formed approximately as shown in Fig. 1, is pointed at its outer extremity and lies in the same plane and parallel with one side of the cutter member. The knife 7, formed at 45 the opposite side of the cutter member, is bent at right angles to the sleeve and is also pointed at its outer extremity. The knife 8, formed at the front of the sleeve 5 on the opposite side from the knife 7, is bent out-

wardly and then parallel with the sleeve 55 so as to lie out of the plane of the knife 6.

The sleeve 5 is provided with a spring 9 riveted thereto, said spring being provided with a projection or pawl 9^a adapted to engage the teeth 4 of the shank to prevent the 60 cutter member from slipping back against the operator's hand when the tool is in use. The spring 9 may be lifted and the pawl 9^a disengaged from the teeth 4 to set the cutter at any desired position. 65

The operation of opening a rectangular can consists in sliding the sleeve member to the outer end of the shank where it is locked in position by the projection or pawl 9^a engaging the teeth 4. The point of the knife 70 6 is then forced through the metal of the can and the handle raised in the usual manner, using the prongs 3 as a fulcrum.

In cutting out the top of a circular tin, the prong on the side adjacent the knife 7 75 is forced through the center of the metal, the sleeve is slid out the required distance, and the knife 7 forced through the metal at the circumference of the can. By moving the tool in a circle, using the prong as a 80 center, the top can be completely cut away, as shown in Fig. 4.

To remove the top of a can in the manner shown in Fig. 5, the opposite prong is forced through the center of the top and the knife 85 8 is slid towards the can until it penetrates the side wall below the seam. The sleeve 90 will be kept in position by the spring catch 9 and the top of the can entirely removed below the seam.

The advantages of this device and its great variety of uses will be apparent.

Having thus described my invention, what I claim is:—

1. A can opener comprising a shank having a pair of prongs at one end thereof, a cutter member slidable on said shank, means for locking said cutter member in position, a knife projecting at right angles to one side of said cutter member, and a pair of knives 100 extending parallel to the opposite side of said cutter member. 95

2. A can opener comprising a shank, a handle therefor, a pair of oppositely disposed prongs on one end of said shank, a cutter sleeve slidable on the shank, said sleeve being provided with a knife projecting at right angles to one side of same, a 105

2

second knife parallel to and in the same plane as the opposite side of said sleeve, and a third knife parallel to but lying out of the plane of said second knife.

5. 3. A can opener comprising a shank, a handle therefor, a pair of prongs on one end of said shank, a cutter sleeve slidable on said shank, said cutter sleeve being provided with an integral knife projecting at right angles to one side of the sleeve, and a pair of forwardly projecting knives parallel to the opposite side of said sleeve, and means for locking said sleeve in position.
10. 4. A can opener comprising a shank a handle therefor, a pair of prongs on one end of said shank, a cutter sleeve slidable on said shank, means for locking said sleeve in position, a knife projecting at right angles to one side of said sleeve, a second knife projecting forwardly in the same plane as the

opposite side of said sleeve, and a third forwardly projecting knife lying parallel to the plane of said second knife.

15. 5. A can opener comprising a shank having a pair of oppositely disposed prongs at one end and a plurality of teeth on the back thereof, a sleeve slidable on said shank having means for engaging said teeth to lock the sleeve in position, a knife projecting at right angles to one side of said sleeve, a second knife parallel to and in the same plane as the opposite side of said sleeve, and a third knife parallel to but lying out of the plane of said second knife.

20. In witness whereof I have hereunto set my hand in the presence of two witnesses.

ARTHUR M. RUSSELL.
